[57] CLAIM

The ornamental design for a cooking and dehydrating device, as shown and described.

DESCRIPTION

FIG. 1 is a front perspective view of a cooking and dehydrating device, showing our new design;
 FIG. 2 is a front elevational view thereof;
 FIG. 3 is a top plan view thereof;
 FIG. 4 is a right side elevational view thereof;
 FIG. 5 is a rear elevational view thereof; and
 FIG. 6 is a bottom plan view thereof.
